KNITTED SHEATH OR CORSET AND PROCESS FOR THE MANUFACTURE OF THE SAME

Edmond Boudios, Paris, France, assignor to
Etablissements Boudios, Romilly-sur-Seine,
Aube, France

Application September 11, 1937, Serial No. 163,487
In France July 1, 1937

8 Claims. (CL 66—176)

In the sheaths, corsets and other knitted goods of known manufacture, the threads, whether elastic or not, which are used as woof threads in the meshes, assume a practically horizontal position when the said articles are worn.

The present invention has for its object a sheath or corset in which the woof threads form, at the front of the article, V-shaped parts whose points are downwardly directed and whose top parts are located on the lateral sides of the said article. Such a sheath or corset is adapted to raise the abdominal organs.

The invention has further for its object a process of manufacture of a sheath or corset of the aforesaid type, in which said article is made of two pieces which are longitudinally assembled according to the middle vertical lines of the back and front; each of the said pieces is obtained by the combination, on the one hand, of transfers, made in the same direction, of the meshes of the two parts of said piece which are situated on either side of a vertical line which is axial or practically axial, and on the other hand, of widenings or narrowings according to the direction of the work upon one of the edges of the piece.

In the accompanying drawing, which is given solely by way of example:

Fig. 1 is a front view of a sheath, according to the invention.

Figs. 2 and 3 are two corresponding diagrams, in elevational and plan views.

Fig. 4 is a diagram showing by way of example, in one of the two pieces forming the knitted sheath, a transfer of meshes to the left, in the two portions of this piece which are located on either side of the vertical axis of the work.

Fig. 5 is a diagram of the same piece, supposed to be flat, and seen on the wrong side, which is obtained by this simple transfer of meshes.

Fig. 6 shows, in the flat position, and seen on the right side, one of the two halves of the sheath represented in Fig. 1, obtained by the combination of transfers of meshes, of widenings on one edge, and of fashioning loops.

In the embodiment shown in Fig. 1, the sheath according to the invention consists of two pieces, P and Q, which are symmetrical with reference to the vertical longitudinal plane whose direction is from front to rear. The two pieces P and Q are assembled in the said plane, at the middle of the back, on the line AB, and at the middle of the front, on the line CD. Each of the pieces is entire, between these two lines, i. e., between the corresponding edges ab and cd. The assembling at AB and CD can be effected by any suitable means, for instance by sewing, by attaching by the use of clasps, hooks, busks, lacing, etc. The two pieces P and Q, which are symmetrical with reference to the plane XX, each comprise an upper ribbed edge 1, then a part 2 in which the rows

of meshes and the woof threads are horizontal and are of decreasing length, owing to transfers of meshes which prevail throughout the entire row and have contrary directions for each of the two parts of the piece situated on the respective sides of a vertical line which corresponds, for each piece, in front view, to the line ef, i. e., to the line of folding when the front part is brought down upon the back. The said transfers correspond to narrowings or to widenings, according to the direction of the work. After this part 2, and clear to the bottom, the rows of meshes and the woof threads remain horizontal in the back part (see gh, Fig. 2) but are placed obliquely in the front part hi, the points i being fairly lower than the rear parts gh, in order to form, with the corresponding threads of the other piece, a series of V-shaped parts whose points i are downwardly directed and situated on the front middle line of connection CD.

The triangular space between the first upper thread h^{11} having its front part oblique, and the last thread h^{12} having its front part horizontal, is filled up by fashioning loops 4.

In like manner, at the lower part, a fashioned portion 5 fills the space between the last lower thread having its front part oblique and the lower horizontal front edge 6 of the sheath.

When the sheath is in place upon the body, it becomes enlarged, and increases from the section S¹ to the section S² (Fig. 3). It will be at once observed that a tension T on a woof thread (Fig. 2) has a horizontal component H producing a centripetal tightening action U (Fig. 3) and a vertical component V (Fig. 2) which produces the desired raising action.

The manufacture of the sheath is effected in the following manner, supposing the knitting begins at the bottom.

The pieces P and Q are knitted separately.

For each piece the ribbed edge 6 is knitted in the known manner. Then the fashioned portions 5 are made. After these latter, there is knitted the part corresponding to the woof threads which extend from one edge ab of the piece to the other cd and whose portions such as hi, which are adapted to form one of the two halves of the front part of the sheath, are disposed obliquely and are directed downward from the rear to the front.

This part of each of the pieces P—Q, which forms the essential feature of the invention, is obtained in the manner shown diagrammatically in Fig. 4, which relates to the piece P seen at the back part, and on which the points represent the different meshes. The vertical line ef is practically the axis of the work, and it corresponds to the lateral outline of the sheath when viewed in front, i. e., to the line of folding of the piece,

if it is supposed that the front part of the sheath is folded upon the rear part.

Let us consider the first two rows of meshes, E and F represented by points as already mentioned. In the next row G, it is supposed that a transfer of meshes has been made to the left, in each of the two halves of the piece, situated on either side of the axis *ef*, with the exception of a few meshes at the middle. The left-hand meshes form an empty space in which are formed two other meshes 1, and the edge becomes inclined at *c'd'* with reference to the axis *ef*. The right-hand meshes have their number reduced by two, and the edge becomes inclined at *ab* in the same direction as the edge *c'd'*. The next row H has no transfer of meshes. The work continues in this manner. The transfers of one or more pairs of divisions take place every *n*th row, and *n* may be variable and may depend upon the form to be given to the piece. Obviously, inextensible or elastic weft threads may be inserted in part or whole of the rows of meshes in known manner as disclosed in the above mentioned U. S. Patent 1,675,691.

If such an operation, performed as above indicated, were pursued as far as the upper thread *i'h'a* (Fig. 5), the result will be the piece *P'*, which is shown diagrammatically in Fig. 5. This piece would have the outline *a b c' d'* (not considering the lower fashioned portions 5 which have been left out of account in this figure). It is visible that if the front portion *h'c' d' f* is folded upon the rear portion *a e f b* about the line *ef*, the line *h'i'* will be inclined downwardly with relation to the line *ea*, and the front edge *c'd'* will assume an oblique position with relation to the edge *ab* which is substantially vertical when the sheath is applied on the body. It is thus necessary to remove from the piece the triangle *i'd'c'* in order that the front edge shall be vertical when the front portion is folded upon the rear portion and shall have a position *cd'* which is practically symmetrical with the edge *ab* with reference to the axis *ef*. This triangle is removed during the knitting operation by making the usual narrowings in the edge of the piece during the progress of the knitting of this part.

However, the simple combination of general transfers to the left and of narrowings of the left-hand edge, would produce a piece in which the upper point of the front edge would be lower than the upper point of the rear edge.

In order to bring these two points to the same level, the fashioning loops 4 will be next produced. Then the part 2 is formed, by making (in known manner) symmetrical transfers of meshes on both halves of the piece which are situated on either side of the axis *ef*, these transfers being made as widenings. The work is finished by the ribbed edge 1, in the known manner.

For the piece Q, the operation is performed in an analogous manner, the general transfers being made to the right, while the narrowings of the edge are made on the right.

It will be noted that owing to the lower fashioned portion 5, the front edge of the pieces P—Q can be straight, or it can have any other form, and for instance, it may be concave as shown at *fp* in Fig. 6.

In like manner, by suitable fashioning, the upper edge *dec* may be given any other form than a practically horizontal line.

Obviously, the different transfers of the meshes and the narrowings (or the widenings if the knitting operation is commenced at the top) may be

carried out entirely by hand or by mechanical devices.

Obviously, the invention is not limited to the embodiments herein described and represented, which are given solely by way of example. The fashioned portions 4 and 5 of the present example might be eliminated, if necessary.

Having now described my invention what I claim as new and desire to secure by Letters Patent is:

1. In a method for manufacturing knitted sheaths, making two symmetrical pieces adapted to be connected together and each obtained by forming a first series of normal rows of meshes, forming on one side of a substantially vertical middle portion of said piece fashioning loops limited on one hand by said first series of rows and one the other hand by a downwardly directed line, forming a second series of rows of meshes while transferring the meshes in a number of rows in the same direction on either side of said substantially vertical middle portion, forming on the same said side of said piece fashioning loops limited on one hand by said second series of rows and on the other hand by a substantially straight line and forming a third series of normal rows of meshes.

2. In a method according to claim 1, the further feature consisting in inserting weft threads in a number of rows of said second series.

3. In a method according to claim 1, the further feature consisting in providing for narrowings and widenings on the edges of said series of rows so as to conform to the desired outline and measures.

4. A knitted sheath made of two symmetrical pieces longitudinally assembled along the middle vertical lines of the back and front, each piece comprising rows of meshes having two portions situated on either side of a substantially vertical plane corresponding to the hips and adapted to be applied on the back and front, the portion corresponding to the back being substantially horizontal and the portion corresponding to the front being inclined downwards starting from said vertical plane.

5. A knitted sheath according to claim 4, further comprising weft threads inserted in said rows of meshes.

6. A knitted sheath made of two symmetrical pieces longitudinally assembled along the middle vertical lines of the back and front and each comprising substantially horizontal upper rows of meshes, intermediate rows of meshes each having a substantially horizontal portion on the rear side of said sheath and a downwardly inclined portion on the front side of said sheath, substantially horizontal lower rows of meshes, fashioning loops on the front side of said sheath between said upper rows of meshes and said intermediate rows of meshes and between said lower rows of meshes and said intermediate rows of meshes.

7. A knitted sheath according to claim 6, further comprising weft threads inserted in a plural number of said intermediate rows.

8. In a method for manufacturing knitted sheaths made of two symmetrical pieces longitudinally assembled along the middle vertical lines of the back and front, the step which consists in forming in each piece rows of meshes while transferring the meshes in a number of rows in the same direction on either side of a substantially vertical middle line.
